[57] CLAIM

The ornamental design of the upper and side portions of a watch/stop watch, as shown.

DESCRIPTION

FIG. 1 is a bottom right front perspective view of the upper and side portions of a watch/stop watch showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a bottom and right-front perspective view of a second embodiment my new design of FIGS. 1-7; and,

FIG. 9 is a front elevational view thereof.

The band-ends, connectors and rear of both embodiments shown in broken-lines are environmental only and form no part of the claimed design.
